Patented Dec. 29, 1964

199,939

ROOFING SHINGLE

Webster Stringer Sidwell, 1029 W. 123rd St.,
Los Angeles, Calif.

Filed June 18, 1962, Ser. No. 70,573

Term of patent 14 years

(Cl. D68—1)

Fig. 1.

Fig. 2.

Fig. 3.

Fig. 4.

Fig. 5.

FIG. 1 is an edge view of a roofing shingle, taken from the top of FIG. 2, showing my new design;

FIG. 2 is a top plan view of the roofing shingle;

FIG. 3 is a bottom plan view thereof;

FIG. 4 is an edge view taken from the bottom of FIG. 3; and,

FIG. 5 is an enlarged right end view of FIG. 3.

The dominant features of my new design reside in the portions shown in full lines.

I claim:

The ornamental design for a roofing shingle, substantially as shown and described.
